UNITED STATES PATENT OFFICE.

AUGUST HUGO GROSSENBACH, OF JERSEY CITY, NEW JERSEY.

DESIGN FOR BRAID AND BRAID-NECKWEAR.

No. 39,174.

Specification for Design.

Patented March 3, 1908.

Application filed January 8, 1908. Serial No. 409,892. Term of patent 3½ years.

To all whom it may concern:

Be it known that I, AUGUST HUGO GROSSENBACH, a citizen of the United States, residing at Jersey City, in the county of Hudson and State of New Jersey, have invented a new, original, and ornamental Design for Braids and Braid-Neckwear, of which the following is a specification, reference being had to the accompanying drawing, forming part thereof.

The figure is a plan view of a braid, showing my new design.

I claim:

The ornamental design for braid and braid neckwear, as shown.

AUGUST HUGO GROSSENBACH.
